CLAIM

The ornamental design for a connector, as shown and described.

DESCRIPTION

FIG. 1 is a perspective view of a connector, showing my new design.

FIG. 2 is a front view of the connector of FIG. 1.

FIG. 3 is a rear view of the connector of FIG. 1.

FIG. 4 is a left side view of the connector of FIG. 1.

FIG. 5 is a right side view of the connector of FIG. 1.

FIG. 6 is a top view of the connector of FIG. 1.

FIG. 7 is a bottom view of the connector of FIG. 1; and, FIG. 8 is a cross-sectional view of the connector taken along line VIII of FIG. 5.

The broken lines shown in FIG. 8 depict the environment of the hose connector and form no part of the claimed design.

1 Claim, 3 Drawing Sheets
